UNITED STATES PATENT OFFICE

NILS GERHARD LINDBORG, OF NEW YORK, N. Y.

METHOD OF AND APPARATUS FOR TREATING VAPORS, GASES, AND THE LIKE

Application filed April 28, 1923. Serial No. 635,201.

This invention relates to a method of and apparatus for treating vapors, gases and the like.

The object of the invention is to provide a method of and apparatus for treating vapors, gases or the like which is simple and effective to obtain therefrom valuable commercial products.

A further object is to effect the condensation of heated vapors and gases in a simple and efficient manner so as to recover therefrom valuable commercial products in liquid or other form.

A further object is to treat heated vapors and gases under a high degree of vacuum to effect economically and thoroughly the condensation and liquefaction of the condensable constituents thereof with the expenditure of a minimum of power.

20 A further object is to create and maintain a maximum degree of vacuum under which condensation of heated vapors or gases may be most expeditiously, reliably and economically effected, and to control the operation, and to render such operation safe, reliable and effective.

Other objects of the invention will appear more fully hereinafter.

The invention consists substantially in the construction, combination, location, relative arrangement of parts and mode of operation, all as will be more fully hereinafter set forth, as shown in the accompanying drawings, and finally pointed out in the appended claims.

35 Referring to the accompanying drawings:

Fig. 1 is a view in vertical central section illustrating one form of apparatus embodying the principles of my invention and suitable for carrying out my improved process.

40 Fig. 2 is a view in horizontal section on the line 2—2, Fig. 1, looking in the direction of the arrows.

Fig. 3 is a detached detail view showing a form of injector elements suitable for use in carrying out my invention and as employed in the illustrative apparatus shown in Fig. 1.

45 Fig. 4 is a similar view of the injector tube employed in connection with the injector elements shown in Fig. 3, parts being shown in section.

Fig. 5 is a similar view showing two of the injector funnels in assembled relation.

Fig. 6 is a top plan view of an injector funnel.

Fig. 7 is a view in section on the line 7—7 55 Fig. 5 looking in the direction of the arrows.

Fig. 8 is a detached detail broken view, parts in section, showing a form of device for automatically controlling the supply of water or other condensing agent employed in 60 carrying out my invention.

Fig. 9 is a view illustrating in side elevation and in bottom plan, a form of cone valve employed in connection with the supply control device disclosed in Fig. 8. 65

Fig. 10 is a view showing in edge elevation and bottom plan the cover plate with offsetting lugs to form a seat for the upper member or head of the injector device.

Fig. 11 is a view in central section of a 70 form of water or condenser medium baffle plate or umbrella.

Fig. 12 is a top plan view of the same.

Fig. 13 is a detached broken detail view showing a form of device for maintaining a 75 constant level of material within the separating chamber, suitable for use in carrying out my invention.

The same part is designated by the same reference numeral wherever it occurs 80 throughout the several views.

In carrying out my invention, I propose to employ a flow of water or other cooling and condensing fluid to exert an aspirating or injector action upon the heated vapors, gases or the like to be treated, within a closed chamber to which such vapors, gases or the like are delivered, to thereby draw such vapors or gases into and carry the same along with the flow of condensing material, thereby cooling and condensing such vapors or gases and enabling the condensed product to be separated and recovered, and at the same time creating a vacuum condition of high degree to facilitate the operation and render the same more effective and economical. I have

90 found that where hydrocarbon vapors are treated, as for instance in the production of lubricants and lubricating oils by distilling crude oil, water is a suitable condensing agent 95 100

to employ, and in accordance with my invention I propose to effect a direct separation of the condensates or elements obtained from the heated hydrocarbon vapors from the water employed to effect the condensation of such vapors, utilizing the difference in specific gravities of the condensates in effecting such separation. I also propose to successively subject the vapors to condensing, scrubbing and absorbing actions under conditions which aid in increasing and maintaining the vacuum under which the operations are carried on, by successively reducing the volume of the gases or vapors, thereby reducing the load on the pump or other means employed to draw the vapors or gases from the distillation or other source and cause the same to pass through the various operations.

In general, in carrying out my invention the heated vapors or gases are delivered or drawn into a closed chamber and therein subjected to the aspirating or injector action of a cooling medium which is caused to flow through such chamber, the cooled vapors or gases passing along with the cooling medium into what I shall call a separating chamber, the vapors or gases and cooling medium being given a whirl within the separating chamber to create eddies which aid in the natural tendency of the condensates to separate from the cooling medium by reason of their differences in specific gravities. I also propose to conduct off the separated condensates and cooling medium while maintaining a substantially constant but controllable level and supply within the separating chamber. The uncondensed gases or vapors, in accordance with my invention, are successively subjected to the condensing or cooling action of suitable media to separate out or absorb therefrom the condensable constituents of such gases or vapors, thereby successively reducing the volume of the gases or vapors under treatment and hence, also, maintaining or even increasing the vacuum condition under which the operations are carried on. In this manner I am enabled to secure an increased efficiency of the condensing operation, reduce the time required to effect the distillation, reduce the fuel required to effect the distillation, avoid the possibility of the gases or vapors remaining too long in the still which would destroy some of the valuable constituents of the gases or vapors, increase the capacity of the output or quantity of condensates recovered as well as enhance the quality thereof, control the viscosity and specific gravity of the recovered products or condensates, and secure and attain many other advantages, and deliver eventually a better quality of gas or vapor after the condensing, scrubbing and absorbing operations have extracted therefrom the recoverable constituents.

It will be apparent that the process of my

invention might well be carried out in a wide variety of forms of apparatus.

While I have shown and will describe my invention as applicable to the treatment of hydrocarbon vapors delivered from a crude oil distilling apparatus, in the production of refined, lubricating and other oils, to which purpose my invention is particularly well adapted, nevertheless my invention is not to be limited or restricted in this respect as it is also suitable for use in treating other vapors or gases.

In the drawings I have shown the closed chambers 1 each of which is designed to be connected through a pipe or other connection 2 with a still, retort or other source of production of the vapors or gases to be treated. I will refer to the chambers 1 as the first vacuum chamber, and while I have shown two such chambers my invention is not to be limited or restricted in this respect.

In accordance with my invention, I propose to maintain a vacuum in the chambers 1, and this may be accomplished in various ways. For example, by subjecting the gases or vapors in said chambers to the condensing effect of a cooling medium so applied as to not only effect a condensing action upon the hot gases or vapors but also an aspirating action tending to draw the gases or vapors into the chamber from the distilling apparatus, and to cause the condensed portion as well as the uncondensed gases and vapors to be drawn from the chamber and carried along with the cooling medium and delivered into a separating chamber indicated at 9, where separation takes place between the condensate products of the vacuum chamber 1, the remaining uncondensed gases or vapors, and the cooling medium employed, as will be more fully described hereinafter.

In practice, I prefer to supply the cooling medium under a hydrostatic head which will augment its action in drawing in and carrying along with it the gases or vapors to be condensed.

I have shown simple and efficient aspirating or injecting apparatus for this purpose which, in the illustrative arrangement shown, consists of a pipe 5, which extends through the chamber 1, being connected at its upper end to a suitable source of supply of cooling medium, say, for example, water. As shown, the upper end of the pipe 5 is connected to a tank or reservoir 40, into which water is supplied from any convenient source through pipe connection indicated at 41. The lower end of the pipe 5 extends into a cup 10. Instead of the pipe 5 being continuous from the tank 40 to the cup 10, I prefer to have it in sections, one of which, indicated at 50, see Fig. 4, has its upper and lower ends threaded respectively into the heads 51 and 52. The pipe section 50 intermediate the heads 51, 52, is provided with a series of openings 53. The

head 51 at the upper end of the pipe section 50 is formed with a central funnel shaped passage 54, the pipe section 50 at its upper end being threaded into the smaller end of the funnel passage 54. The heads 51, 52, are 5 preferably tapered from their midlength portions towards each end, as clearly shown in Figs. 3 and 4, the tapered portions having slits or openings 55 to the central bores thereof. The upper tapered end of head 51 is seated 10 against and centered by a series of lugs 56, mounted upon the under surface of the top or cover of the chamber 1. The upper section of pipe 5 passes through an opening in 15 this top or cover and registers with the funnel bore 54 of the head. In like manner, the lower tapered end of head 52 is seated upon and centered by lugs 57, on the upper surface of the bottom of chamber 1. Intermediate 20 the heads 51, 52 and strung upon the pipe section 50 are a series of funnel shaped members 4, as shown in Figs. 5, 6 and 7. Each member 4 is formed with an upper funnel shaped portion within which are arranged 25 lugs 58, which form a centering seat for the lower tapered portion of the member 4 next above it when assembled in nested relation thereto, said lugs also serving to offset the nesting surfaces of the members from each 30 other. Each member 4 is also provided with an annular flange 59, through which are formed slots 60, which open into the funnel bore of the next adjacent member 4 into which it is nested. The bores of the members 4 35 register with the openings 53 in the pipe section 50.

In the manner above described, the vacuum producing means are assembled within the chambers 1, the pipe section 50, constituting the body of such means, forming a passage through which the cooling medium flows under the influence of gravity and of the hydrostatic head of the medium. The flow of the cooling medium through the pipe section 40 50 exerts an injector action upon the gases or vapors in chamber 1, through the openings 53 and slots 60, thereby drawing the gases or vapors into the pipe section and carrying the same along with the flow of cooling medium through said pipe section. This not only 45 cools and partially condenses the hot gases and vapors, thereby reducing the volume thereof, but it also creates and maintains a high degree of vacuum within chamber 1, and 50 hence exerts a strongly pulling force upon the gases or vapors to draw the same from the distilling apparatus. Thus are realized 55 rapidity of operation, a reduced amount of fuel for operating the distilling apparatus, and avoidance of losses in leaving the gases or vapors for too long a time in the distilling apparatus. The provision of the openings 55, in head 51, permits the hottest and most 60 highly expanded gases or vapors entering 65 the chamber 1, and which naturally would

tend to collect in the upper portion of said chamber, to be quickly drawn into the vacuum body and into the stream of cooling medium at the coolest part of the latter. This very greatly increases the efficiency of the apparatus. Whatever precipitation of condensates takes place within the chamber 1 collects in the bottom of said chamber, and the openings 55 in head 52 permit such condensates to be instantly drawn into the stream 70 of cooling medium flowing through said head, thus again adding to the efficiency of the apparatus and aiding in maintaining the high vacuum within chamber 1. In practice, I prefer to form the bore of the head 52 with 75 an enlarged chamber 61, see Fig. 4. This permits the stream of cooling medium to break by expansion into this chamber, thereby bringing the gases, vapors and condensates 80 into more intimate contact with the cooling 85 medium.

It is preferable to create eddies or whirls in the mass of cooling medium and condensates delivered from the vacuum chambers 1 into the separating chamber 9. This can 90 be accomplished in various ways. A simple arrangement is shown wherein the rim of the upper open ends of the cups 10, are provided with tangentially arranged slots 46. In operation the cooling medium, condensates, gases, and vapors are delivered by the pipe 5 into the open cup 10, which fills up, the uncondensed gases or vapors bubbling up through the contents of the cup, thereby aiding materially in effecting the desired 95 condensing and precipitating action, said gases and vapors eventually tending to collect in the upper portion of chamber 9, and being further treated as will presently be more fully explained. At the same time the cooling medium along with the condensates spill 100 over the rim at the upper open end of cup 10, a portion thereof spilling through the tangential slots 46, thereby creating the whirls or eddies in the bdy of the substances which 105 collect in the chamber 9. Not only does the cup arrangement impart eddies or whirls to the cooling medium and condensates, but it also forms a water seal or lock to prevent any back flow into pipe 5 of gases or vapors 110 from chamber 9. By reason of the eddies or whirls produced in the liquid delivered into chamber 9, the condensates of lighter specific 115 gravity are enabled to rise and float on the top of the cooling medium and are propelled 120 towards the center of chamber 9, and are thus prevented from forming an emulsion with the cooling medium or from being retained within the body of the mass of cooling medium.

Disposed within chamber 9 is a curved partition wall 23 associated with each cup 10, and in such relation to each other as to form restricted passageways 62 between each other, which passageways form a guide path by 125

which the cooling medium, with the condensates floating on the surface thereof, is directed to the center of the chamber 9. Interposed in these guiding channels are suitable resistances 47, the function of which is to break up the eddies or whirls in the mass of liquid and facilitate the separation of the condensates from the cooling medium. In the illustrative arrangement shown, these resistances are in the form of fluted or corrugated sheets disposed in parallel relation to each other within and in the direction of length of the restricted passages 62, the travel of the liquids through said passages towards the center of the chamber 9 being past and between said sheets or plates.

The condensates floating on the top of the mass of cooling material, and as well, the cooling medium itself, which are constantly being delivered into chamber 9, may be drawn off from said chamber in any suitable or convenient way. In the case of the cooling medium I have shown an exhaust pipe 25 extending into chamber 9, and having its inner end bent down into a depression 26 formed in the bottom of said chamber. The hydrostatic head of the liquid contained in said chamber 9, forces the cooling medium to flow out through the exhaust pipe 25. If desired, said pipe may have a bend therein, as indicated at 63, to form a trap to prevent reverse flow.

In the case of the condensates, I provide an exhaust or drawing-off pipe connection 24, having also a reverse bend 64 to form a trap, and I provide means at the inner end of the draw-off pipe to control the height of the level of the mass of liquid within chamber 9. In the illustrative arrangement shown, the inner end of the draw-off pipe 24 is upturned and an open ended sleeve 11 telescopes thereover. This sleeve is carried by a rack bar 27, see Figs. 1 and 13, which is engaged by a pinion 65 on a shaft 66, which extends through the wall of chamber 9 and carries a hand wheel 28 by means of which said shaft may be rotatively adjusted so as to raise or lower the sleeve 11, thereby adjusting the height to which the level of the contents of chamber 9 must rise before draw-off occurs through pipe 24.

As above described, the uncondensed gases or vapors delivered into chamber 9 tend to collect in the upper part of the chamber. In order to remove from such gases or vapors any other condensable content thereof, I prefer to subject the same again to the action of a cooling medium. To this end a condenser chamber 12 opens freely into the upper part of chamber 9, preferably through the top thereof, and the gases or vapors instead of collecting and remaining in chamber 9, ascend into and pass through the chamber 12. A cooling medium, such for example as water, is admitted into the upper end of the chamber 12, as, for instance, through a spray-

ing device 14, so that the ascending gases or vapors meet a descending spray of cooling medium thereby most thoroughly condensing the remaining condensable constituents of the gases or vapors, the condensates being carried down with the cooling medium into the chamber 9. In practice I prefer to fill the chamber 12 with suitable material adapted to exert a scrubbing action upon the gases or vapors percolating therethrough. I have found that broken particles of coke, pumice stone, brick and the like will answer the purpose, and in order to support and retain the scrubbing material in chamber 12, I provide said chamber with a perforated bottom as indicated at 13 in Fig. 1.

It is undesirable to permit the cooling medium which is employed in chamber 12, and the condensates carried down with such medium, to be precipitated directly into the separating chamber 9 as that would create agitation of the contents of chamber 9 and prevent the proper efficient and expeditious separation of the condensates from the cooling medium. To prevent this I mount an umbrella-shaped shield or baffle plate 16 in the upper part of chamber 9, the diameter or dimension of the rim or boundary edge of said shield being smaller than the internal dimension of the chamber 9 as is shown in Fig. 1. This affords an opportunity for the cooling medium and condensates from chamber 12 to be deflected downwardly along the upper surface of the shield and to spill over the rim or boundary edge of said shield and to trickle or flow down the inner surface of the side walls of chamber 9 thereby avoiding any agitation of the contents of the said chamber 9. It will also be observed that the gases or vapors in chamber 9 must also pass around the outer rim or edge of shield 16 in reaching the chamber 12 from chamber 9. This is advantageous for the reason that the cooling medium entering chamber 9 from chamber 12 is cooler than that entering chamber 9 from chamber 1, since the temperature of the gases or vapors in chamber 12 is reduced below that of the gases or vapors in chamber 1. Therefore the cooling medium supplied from chamber 12 is better able to effect its condensing action upon the gases or vapors not only in chamber 12, but also in chamber 9, this also aids very materially and substantially in maintaining a high vacuum condition in both said chambers 9 and 12, and hence augments the efficiency of operation of the entire system.

It is important that an efficient seal or lock be maintained to prevent the back flow of gases or vapors from chamber 9 into chamber 1. This, as above explained, is one of the functions of the cups 10. To enable these cups to accomplish their functions in this respect, it is necessary that said cups be constantly maintained full of cooling me-

dium or mixture of cooling medium and condensates. To insure this result in one illustrative and practical arrangement, I provide the upper surface of the shield 16 with raised ledges 18, see Fig. 12, so disposed as to form pan or dish portions 67 in said upper surface. These pan or dish portions are disposed over the cups 10, and are provided with openings 17, directly over said cups. 5 With this arrangement the cooling medium and condensates delivered from chamber 12, keep these pan or dish portions constantly filled and the openings 17 permit the same to pour directly into the cups 10, thereby insuring that the cups 10 are kept constantly filled to enable them to form seals or locks even if, for any cause, there should be a failure of a supply of cooling medium and condensates to said cups from the chamber 1. 10

It is desirable to control the supply of cooling medium to the vacuum devices in chambers 1. I have shown various arrangements for this purpose. Thus, in Fig. 1, I have shown the upper and lower portions of pipes 5 provided with manually controlled valves 6, 8. It may sometimes be desirable to effect an automatic control of the supply of the cooling medium and I have shown various ways of effecting such automatic control by 25 the height of level of the liquid in chamber 9. In the arrangement shown a float 32 is arranged to operate in a chamber 68 which is in communication with the interior of chamber 9 through the connections 30, 31, whereby 30 the position of the float is controlled by the height of level of the liquid in chamber 9. The movements of this float are utilized to effect the control of the supply of cooling medium. This is effected, in the arrangement shown, by means of a bar 33 connected to the float 32, said bar effecting the control 35 of a valve 7 in pipe 5, through suitable intermediate connections, such as levers 37, 38, 39. According to another control arrangement, 40 the supply of cooling medium from a supply tank 40 into the upper end of the pipe 5 is controlled by a cone valve 69, which, if desired, may be protected by a screen 44. The valve 69 cooperates with a cone seat 42 at the bottom of the tank 40 which is in register with the pipe 5. The seating and unseating of this control valve may be effected automatically in any desired or suitable manner. I have shown this accomplished and controlled by 45 variations in the level of the liquid contained in chamber 9, and to this end I utilize the movements of the float 32 in auxiliary chamber 68. In that case the bar 33 is in the form of a rack bar which meshes with and rotates 50 a pinion 34, on a shaft 36, upon which shaft is carried a drum 35 which operates a flexible cable or other connection 45 connected to valve 69. If desired, and in order to still further treat 55 the gases or vapors which remain after passing through chamber 12, said gases or vapors may be subjected to further condensing, scrubbing or absorption action, as conditions may require. For this purpose the gases or vapors pass from chamber 12 through pipe 70 connection 70 into the lower end of a chamber 18^a in which, if desired or required, is arranged a perforated supporting plate 19 for a mass of scrubbing material, such as broken particles of coke, stone, brick or the like, the gases or vapors being drawn from the upper end of chamber 18^a through connection 20, to which is connected a pump (not shown). Any suitable absorbent material may be employed to the action of which the gases or vapors passing through chamber 18^a are subjected. For example, where hydrocarbon oil vapors are under treatment I have found that absorbent oil serves the purpose of an absorbent. The absorbent material is introduced into the top of the chamber 18^a, through a spray device 22, and it collects in the bottom of said chamber, along with any constituent of the gases or vapors which it might absorb, and may be drained off 80 through drain connection 21. 75

In order to provide against injury to the apparatus or interruption of its operation on account of the development of internal pressure through accident or otherwise it is desirable to provide one or more suitably located safety relief valves to atmosphere. I have indicated such a safety relief valve at 15 in Fig. 1, as associated with and connected to the upper end of the chamber 12. 90

It is believed that the operation and mode of procedure in carrying out my invention will be readily understood by persons skilled in the art from the foregoing description taken in connection with the accompanying drawings. 95

It will be understood that my invention in its broadest scope as defined in the claims, is not to be restricted to the exact details of structure and mode of operation shown and described, as the same may be modified and changed throughout a wide range without departing from the spirit and scope of my invention. 100

But having now set forth the objects and nature of my invention, and the manner of carrying the same into operation, what I claim as new and useful and of my own invention and desire to secure by Letters Patent is: 110

1. The method of treating heated gases or vapors which consists in subjecting the same to the action of a cooling medium under vacuum then imparting eddies to the resulting mass of condensates and cooling medium, 115 and then isolating the condensates. 120
2. The method of treating heated gases or vapors which consists in subjecting the same to the action of a cooling medium under vacuum, then imparting eddies to the result- 130

- ing mass of condensates and cooling medium, then breaking up the eddies and isolating the condensates.
3. In an apparatus for condensing heated gases or vapors, a chamber to receive the gases or vapors, a pipe extending through said chamber, said pipe having openings into said chamber, means to cause a stream of cooling medium to flow through said pipe, said openings acting to permit the gases or vapors to be drawn into said pipe and carried along with the flow of the cooling medium, and a trap or seal for the end of the pipe to prevent the reverse flow of the gases or vapors through said pipe. 70
- 15 4. In an apparatus for condensing heated gases or vapors, a chamber to receive the gases or vapors, a pipe extending through said chamber and having openings in the wall thereof, a series of members having funneled bores communicating with said chamber, said bores registering with the openings in said pipe, and means to cause a stream of cooling medium to flow through said pipe. 75
- 20 5. In an apparatus for condensing heated gases or vapors, a chamber to receive the gases or vapors, a pipe extending through said chamber, said pipe having a section thereof located within said chamber and formed with openings through the wall thereof, aspirating members carried by said pipe section communicating with said chamber and registering with said pipe section openings, and means to cause a stream of cooling medium to flow through said pipe. 80
- 25 6. In an apparatus for condensing heated gases or vapors, a chamber to receive the gases or vapors, a pipe extending through said chamber, said pipe having openings in the wall thereof, a head located within said chamber and centered therein, said head having openings into the chamber and registering with the openings in said pipe, and means to cause a stream of cooling medium to flow through said pipe. 85
- 30 7. In an apparatus for condensing heated gases or vapors, a chamber to receive the gases or vapors, a pipe extending through said chamber, said pipe having a section thereof located within said chamber and formed with openings through the wall thereof, a head located within said chamber and to which said pipe section is connected, said head having openings into the chamber, and means to cause a stream of cooling medium to flow through said pipe. 90
- 35 8. In an apparatus for condensing heated gases or vapors, a chamber to receive the gases or vapors, a pipe extending through said chamber, said pipe having a section thereof located within said chamber and formed with openings through the wall thereof, a series of members each having a funneled bore mounted on said pipe section, said bores communicating with the chamber and with the 95
- openings in said pipe, and means to cause a stream of cooling medium to flow through said pipe section.
9. In an apparatus for condensing heated gases or vapors, a chamber to receive the gases or vapors, a pipe section located within said chamber and having aspirating openings through the wall thereof communicating with said chamber, means to cause a stream of cooling medium to flow through said pipe section, and a head connected to the delivery end of said pipe section and having an enlarged central bore or opening registering with said pipe section. 100
- 10 10. In an apparatus for condensing heated gases or vapors, a chamber to receive the gases or vapors, a pipe section located within said chamber, a head connected to the intake end of said pipe section, said head having a bore in register with said pipe, and having openings therethrough into the chamber, and means to cause a stream of cooling medium to flow through said pipe section. 105
11. In an apparatus for condensing heated gases or vapors, a chamber to receive the gases or vapors, a pipe section located within said chamber, a head connected to the discharge end of said pipe section, said head having a bore in register with said pipe, and having openings into the chamber, and means to cause a stream of cooling medium to flow through said pipe section. 110
12. In an apparatus for condensing heated gases or vapors, a chamber to receive the gases or vapors, a separating chamber, a pipe extending through said gas or vapor receiving chamber into the separating chamber and having aspirating communication therewith, said pipe delivering into said separating chamber, and means to cause a stream of cooling liquid to flow through said pipe. 115
13. In an apparatus for condensing heated gases or vapors, a chamber to receive the gases or vapors, a separating chamber, a pipe extending through said gas or vapor receiving chamber and having aspirating communication therewith, said pipe delivering into said separating chamber, means to cause a stream of cooling liquid to flow through said pipe, and a liquid seal interposed between the delivery end of said pipe and said separating chamber. 120
14. In an apparatus for condensing heated gases or vapors, a chamber to receive the gases or vapors, a separating chamber, a pipe extending through said gas or vapor receiving chamber into the separating chamber, and having aspirating communication therewith, said pipe delivering into said separating chamber, means to cause a stream of cooling liquid to flow through said pipe, and means to create eddies in the liquid delivered by said pipe into said separating chamber. 125
15. In an apparatus for condensing heated gases or vapors, a chamber to receive the gases 130

or vapors, a separating chamber, a pipe extending through said gas or vapor receiving chamber and having aspirating communication therewith, said pipe delivering into said separating chamber, means to cause a stream of cooling liquid to flow through said pipe, and means to facilitate the separation of condensates from the cooling liquid in said separating chamber, said means including a guiding plate to direct the liquid delivered from said pipe towards the center of said separating chamber.

16. In an apparatus for condensing heated gases or vapors, a chamber to receive the gases or vapors, a separating chamber, a pipe extending through said gas or vapor receiving chamber into the separating chamber and having aspirating communication therewith, said pipe delivering into said separating chamber, means to cause a stream of cooling liquid to flow through said pipe, means to facilitate the separation of condensates from the cooling liquid in said separating chamber, said means including a guiding plate to direct the liquid delivered from said pipe towards the center of said separating chamber, and means in the path of movement of said liquid towards the center of the separating chamber to interrupt eddies in said liquid.

17. In an apparatus for condensing heated gases or vapors, a chamber to receive the gases or vapors, a separating chamber, a pipe extending through said gas or vapor receiving chamber, and having aspirating communication therewith, said pipe delivering into said separating chamber, means to cause a stream of cooling liquid to flow through said pipe, and means controlled by the height of level of the liquid in said separating chamber to control the supply of cooling medium to said pipe.

18. In an apparatus for condensing heated gases or vapors, a chamber to receive the gases or vapors, a separating chamber, a pipe extending through said gas or vapor receiving chamber, and having aspirating communication therewith, said pipe delivering into said separating chamber, means to cause a stream of cooling liquid to flow through said pipe, a float controlled by the level of liquid in said separating chamber, and means actuated by said float to control the supply of cooling medium through said pipe.

19. In an apparatus for condensing heated gases or vapors, a chamber to receive the gases or vapors, a separating chamber, a pipe extending through said gas or vapor receiving chamber, and having aspirating communication therewith, and a cup arranged in said separating chamber into which said pipe delivers, said cup forming a liquid seal between said chambers.

20. In an apparatus for condensing heated gases or vapors, a chamber to receive the

gases or vapors, a separating chamber, a pipe extending through said gas or vapor receiving chamber, and having aspirating communication therewith, and a cup arranged in said separating chamber into which said pipe delivers, said cup forming a liquid seal between said chambers, the rim of said cup having tangential slots to impart a whirl to the liquid spilling over the same into the separating chamber.

21. In an apparatus for condensing heated gases or vapors, a chamber to receive the gases or vapors, a separating chamber, a pipe extending through said gas or vapor receiving chamber, and having aspirating communication therewith, said pipe delivering into said separating chamber, means to cause a stream of cooling liquid to flow through said pipe in combination with a second chamber arranged to receive the uncondensed gases or vapors from said separating chamber, and means to supply a cooling medium to said second chamber.

22. In an apparatus for condensing heated gases or vapors, a chamber to receive the gases or vapors, a separating chamber, a pipe extending through said gas or vapor receiving chamber, and having aspirating communication therewith, said pipe delivering into said separating chamber, means to cause a stream of cooling liquid to flow through said pipe in combination with a scrubbing chamber communicating with the upper part of said separating chamber to receive the uncondensed gases or vapors therefrom.

23. In an apparatus for condensing heated gases or vapors, a chamber to receive the gases or vapors, a separating chamber, a pipe extending through said gas or vapor receiving chamber, and having aspirating communication therewith, said pipe delivering into said separating chamber, means to cause a stream of cooling liquid to flow through said pipe in combination with a scrubbing chamber communicating with the upper part of said separating chamber to receive the uncondensed gases or vapors therefrom, and means to deliver a spray of cooling liquid into said scrubbing chamber.

24. In an apparatus for condensing heated gases or vapors, a chamber to receive the gases or vapors, a separating chamber, a pipe extending through said gas or vapor receiving chamber, and having aspirating communication therewith, said pipe delivering into said separating chamber, means to cause a stream of cooling liquid to flow through said pipe in combination with a scrubbing chamber communicating with the upper part of said separating chamber to receive the uncondensed gases or vapors therefrom, means to deliver a spray of cooling liquid into said scrubbing chamber, and means to conduct the discharge from said scrubbing chamber to

the inner surface of the side walls of the separating chamber.

25. In an apparatus for condensing heated gases or vapors, a chamber to receive the gases or vapors, a separating chamber, a pipe extending through said gas or vapor receiving chamber, and having aspirating communication therewith, said pipe delivering into said separating chamber, means to cause a stream 10 of cooling liquid to flow through said pipe in combination with a scrubbing chamber communicating with the upper part of said separating chamber to receive the uncondensed gases or vapors therefrom, means to deliver a spray of cooling liquid into said scrubbing chamber, and a baffle plate member interposed between the scrubbing and separating chambers.

26. In an apparatus for condensing heated gases or vapors, a chamber to receive the gases or vapors, a separating chamber, a pipe extending through said gas or vapor receiving chamber, and having aspirating communication therewith, a cup arranged in said separating chamber into which said pipe delivers, said cup forming a liquid seal between said chambers in combination with a scrubbing chamber arranged to receive the uncondensed gases or vapors from said separating chamber, means to supply a cooling medium 30 into said scrubbing chamber, and means to deliver liquid from the scrubbing chamber into said cup.

27. In an apparatus for condensing heated gases or vapors, a chamber to receive the gases or vapors, a separating chamber, a pipe extending through said gas or vapor receiving chamber, and having aspirating communication therewith, a cup arranged in said separating chamber into which said pipe delivers, said cup forming a liquid seal between said chambers in combination with a scrubbing chamber arranged to receive the uncondensed gases or vapors from said separating chamber, means to supply a cooling medium 45 into said scrubbing chamber, and means to deliver liquid from the scrubbing chamber into said cup including a baffle plate located in said separating chamber, and having an opening disposed in line with said cup.

28. In an apparatus for condensing heated gases or vapors, a chamber to receive the gases or vapors, a separating chamber, a pipe extending through said gas or vapor receiving chamber, and having aspirating communication therewith, a cup arranged in said separating chamber into which said pipe delivers, said cup forming a liquid seal between said chambers in combination with a scrubbing chamber arranged to receive the uncondensed gases or vapors from said separating chamber, means to supply a cooling medium 55 into said scrubbing chamber, and means to deliver liquid from the scrubbing chamber into said cup including a baffle plate having a pan or

dish provided with an opening therein arranged in line with said cup.

29. In an apparatus for condensing heated gases or vapors, a chamber to receive the gases or vapors, a separating chamber, a pipe extending through said gas or vapor receiving chamber and having aspirating communication therewith, said pipe delivering into said separating chamber, means to cause a stream 70 of cooling liquid to flow through said pipe in combination with a scrubbing chamber communicating with the upper part of said separating chamber to receive the uncondensed gases or vapors therefrom, an absorbing chamber to receive uncondensed gases 75 or vapors from said scrubbing chamber, and means to supply an absorbent to said absorbing chamber.

In testimony whereof I have hereunto set my hand on this 26th day of April A. D. 1923. 85

NILS GERHARD LINDEBORG.
